ROTARY SWAGER WITH AXIALLY PROGRESSIVE DIE ACTION

Sidley O. Evans, Beaver Falls, Pa., assignor, by
mesne assignments, to The Babcock & Wilcox
Company, Jersey City, N. J., a corporation of
New Jersey

Application November 22, 1950, Serial No. 197,083

11 Claims. (Cl. 78—21)

1

This invention relates to swaging means of the rotary spindle type, as used for reducing the diameter of tubes, rods and the like or for forming a point on such elements.

These swaging machines include a rotary spindle having an axially extending diametric slot in which are mounted opposed dies. Surrounding the spindle is an annular series of striker rolls, the rolls being confined between the spindle and an outer ring, and frequently held in separated relation by a race. Each die has associated therewith a hammer block, likewise mounted in the spindle slot, and the radially outer ends of the hammer blocks are provided with striker means, such as a roll mounted in the hammer block.

The relative arrangement and relation of parts is such that, when a workpiece is inserted in the axial passage of the spindle, there is a negative clearance between each striker roll and the striker means and the hammer blocks. Consequently, as the spindle is rotated, the striker means of the hammer blocks are recurrently engaged by the striker rolls each time a hammer block and its associated die are radially aligned with a striker roll. The result is a sharp blow struck on the workpiece, reducing the diametric or transverse dimension of the latter.

In known arrangements used in practice, each striker roll extends at least the full length of the slot, and the striker roll axes are parallel to the spindle axis and to the striker means of the hammer blocks. Consequently, the striker roll pressure is exerted simultaneously along the full length of the hammer block and thus along the full length of the die. Thus, the total effective force of each striker roll is divided over the area of the workpiece in contact with the dies, or the average pressure exerted on the workpiece in pounds per square inch is the total force exerted by the machine divided by the total area of die contact.

The present invention is directed to improved die block and hammer block arrangements in which the total force of each recurrent blow by a striker roll is progressively exerted axially along the area of the workpiece in contact with the die block. In one arrangement according to the present invention, the pair of die blocks and the pair of hammer blocks of a conventional rotary swager are replaced by segmental die blocks and segmental hammer blocks. In effect, each die block and hammer block is divided into a series of axially aligned juxtaposed segmental die blocks and hammer blocks. Each hammer block

5
10
15

carries a roll in its outer end for engagement with the striker rolls and, proceeding from one end of the spindle axially toward the other end thereof, the hammer block rolls are progressively off-set circumferentially in the same direction. Consequently, each hammer block roll is successively engaged by a striker roll, with the result that the total effective force is successively concentrated on each segmental die. Thereby, successive increments of the workpiece have full force of the machine applied thereto.

20
25
30
35

In this way, the full force of the machine will be exerted over a small area of the workpiece, and the machine will be exerting its full force for a greater portion of the time since it will exert maximum force several times as the die sets move into radial alignment with any one striker roll. In addition to more effective use of the force of the machine, the flow of metal in the workpiece will not be impeded by confinement or by friction with a relatively long die. In effect, a small high pressure area travels along the workpiece in much the same manner as occurs in rolling of metal.

40
45
50

In another modification of the machine, the conventional die and hammer block sets are replaced by novel die and hammer block sets each comprising a single pair of dies and a single pair of hammer blocks. The work contacting surfaces of the dies, instead of being parallel to the spindle axis are curved longitudinally about relatively large radii of curvature so that the opposed dies rock on each other. Each hammer block has, on its outer end or surface, a striker rib which extends diagonally of the hammer block from one end thereof to the other.

40
45

With this arrangement, as each die and hammer block set moves toward radial alignment with a striker roll, the striker roll progressively engages incremental surface portions of the rib. The total force of the machine is thus progressively exerted on incremental areas proceeding from one end of the workpiece to the other, the opposed dies rocking about their curved surfaces during such progressive application of the striker roll force.

50

For an understanding of the invention principles, reference is made to the following description of typical embodiments thereof as illustrated in the accompanying drawings.

In the drawings:

Fig. 1 is a side elevation view, partly in section, of a rotary swager embodying one form of the invention;

Fig. 2 is an outer end view of the rotary swager shown in Fig. 1, with cover removed;

Fig. 3 is an enlarged end elevation view of the die and hammer block construction shown in Figs. 1 and 2;

Fig. 4 is a diametric sectional view on the line 4—4 of Fig. 3;

Fig. 5 is a sectional view on the line 5—5 of Fig. 4;

Fig. 6 is a view similar to Fig. 3 illustrating another modification of the invention;

Fig. 7 is a side elevation view of a pair of die and hammer block sets used in the arrangement of Fig. 6; and

Fig. 8 is a plan view of the striker surface of the hammer blocks shown in Figs. 6 and 7.

Referring to Figs. 1 through 5, the rotary swager comprises a main frame 10, in the intermediate portion of which is mounted a horizontally disposed spindle 11 suitably supported on antifriction bearings. Fixed adjacent one end of the spindle is a sheave (not shown) operatively connected by a series of belts 13 to a sheave 12 driven by an electric motor 14 which is supported on a platform 16 on the upper portion of the main frame 10.

At the opposite end of the spindle 11 is an enlarged annular head 15 which is formed with a transverse or diametric slot 17 to receive a pair of sets of die blocks each having a set of hammer blocks associated therewith and disposed outwardly of the die blocks. In the illustrated embodiment, each set or series of die blocks comprises four (4) segmental die blocks 20a, 20b, 20c and 20d which are in longitudinal alignment in the slot 17 and juxtaposed axially of the head 15. The die blocks of each pair have complementary semi-circular grooves 18, and the outer ends of the outermost die blocks 20a flare or taper outwardly as indicated at 21. A tube, rod or other metal workpiece (not shown) is introduced between the die blocks and is fed into the machine from the outer end and thence passed axially through the bore 22 of the spindle as will be readily understood by those skilled in the art.

Each die block has associated therewith a segmental hammer block such as 25a, 25b, 25c and 25d, the segmental hammer blocks being aligned longitudinally of slot 17 and in juxtaposed relation. Each hammer block has its outer end wall 26 curved and is formed with a recess 27 to receive a hammer roll such as 28a, 28b, 28c, and 28d. A portion of the peripheral surface of each hammer roll projects outwardly of the curved end wall 26. The hammer rolls are mounted in their respective hammer blocks in such a manner that they are able to turn in order to present different surface portions to be struck by the striker rolls.

Spaced radially from the peripheral surface of the spindle head 15 is a hardened inner or liner ring 31 suitably secured to the main frame 10. Disposed in the cavity 32 between the liner ring 31 and the spindle head 15 is an annular series of striker rolls 30, the rolls 30 being spatially positioned by a race 33. Each striker roll extends at least the full length of and somewhat beyond the slot 17 in head 15, and the striker roll axes are parallel to the spindle axis and thus longitudinally alignable with the sets of segmental die blocks and segmental hammer blocks.

In accordance with the present invention, the successive hammer rolls are progressively offset

circumferentially proceeding from the outer end of the spindle toward the inner end thereof. Thus, and as best seen in Figs. 3, 4 and 5, the leading hammer roll 28a is, as seen in Fig. 3, disposed slightly to the right or clockwise of the axial plane through the slot 17. Referring to Fig. 5, the trailing hammer roll 28d is disposed to the left or counterclockwise of the central or axial plane through slot 17. The intermediate hammer rolls 28b and 28c are spaced uniformly from each other and intermediate the leading roll 28a and trailing roll 28d.

Consequently, when spindle 11 is rotated, each striker roll 30 first engages the leading roll 28a so that the full working force of the machine is directed upon the relatively small length of the workpiece in the leading dies 28a. As the spindle rotates, each striker roll successively engages the following hammer rolls 28b, 28c and 28d in turn directing the full force of the machine on the relatively small area of the workpiece contained within the following dies 28b, 28c and 28d. The full force of the machine is thus exerted in an axially progressing manner along the workpiece, whereby there is a very high concentration of force on each successive incremental length of the workpiece. This successive movement of the dies is recurrently and cyclically repeated as each striker roll 30 engages the leading hammer roll 28a.

A primary advantage of the invention arrangement just described is that the segmental die blocks and hammer blocks may be readily and easily substituted for the usual pair of die blocks and hammer blocks in a conventional rotary swager without any alteration of the swager whatever. Thus, there is no change in the construction of the spindle or its enlarged head 15, or in the arrangement of striker rolls 30. This is an important advantage from the economical standpoint in that expensive reconstruction of the swager structure is unnecessary.

Figs. 6, 7 and 8 illustrate an alternative embodiment of the invention in which the total machine force is progressively exerted on adjacent incremental areas of the workpiece by means of a single pair of dies. In this case, the usual die blocks and hammer blocks are replaced by a pair of die blocks 40 each associated with a novel hammer block 45, the blocks 40 and 45 being mounted in the usual slot 17 in the head 15 of the spindle. The hammer and die blocks may be suitably interlocked against longitudinal shifting in any manner, such as indicated at 41.

The inner surfaces 42 of die blocks 40 are curved longitudinally about very large radii so that these surfaces may rock on each other, this feature being best illustrated in Fig. 7. In the normal position of die blocks 40, the forward edges 43 thereof are in engagement and the rear edges 44 are somewhat separated. As the machine force is progressively applied to the workpieces by each succeeding striker roll 30, the die blocks 40 are rocked rearwardly so that the forward edges 43 separate and the rear edges 44 approach each other, finally meeting.

The workpiece is inserted, in the usual manner, in complementary semi-circular grooves 46, 46 in surfaces 42.

Progressive die squeezing action is effected by a novel striker arrangement on the outer surface 47 of each hammer block 45. The outer surfaces 47 lie generally in the peripheral surface of the block 15, except for their longitudinal

edges 43, 48 which are beveled. Referring more particularly to Figs. 6 and 8, a rib shaped striker element 50 extends diagonally across each surface 47, starting from the leading edge of surface 47 adjacent the outer end of block 45 and extending to the trailing edge at the inner end of block 45. Ribs 50 are preferably semicylindrical although other shapes may be used.

With a workpiece in the machine, the ribs 50 lie within the path of the rolls 30 so that the ends 43, 48 of the die inner surfaces are somewhat separated. Each roll 30 first engages the leading end 51 of a rib 50 delivering the initial impact to the area of the workpiece at the outer end of dies 40. The impact is then progressively applied along the entire length of the workpiece within the dies 40, the die blocks 40 being rocked rearwardly as the roll progressively engages additional increments of the striker rib 50, the striker roll finally releasing the rib 50 at trailing end 52.

While specific embodiments of the invention have been shown and described in detail to illustrate the application of the invention principles, it will be understood that the invention may be otherwise embodied without departing from such principles.

I claim:

1. In a swaging machine, a rotary spindle having an axially elongated diametrically extending slot therein; die block means mounted in said slot for movement radially of said spindle; an annular series of striker rolls embracing said spindle, each striker roll extending parallel to the spindle axis and axially beyond each end of the slot; and hammer block means mounted in said slot and each associated with a die block means, the hammer block means having striker means projecting radially beyond said spindle for recurrent engagement by successive striker rolls; the striker means of each hammer block means being progressively offset circumferentially of the spindle from one end of the hammer block means to the other end thereof; whereby each striker means is progressively engaged by each striker roll so that force is progressively applied longitudinally of each die block means.

2. In a swaging machine, a rotary spindle having an axially elongated diametrically extending slot therein; die block means mounted in said slot for movement radially of said spindle; an annular series of integral striker rolls embracing said spindle, each striker roll extending parallel to the spindle axis and axially beyond each end of the slot; and hammer block means mounted in said slot and each associated with a die block means and in radial alignment therewith the hammer block means having striker means projecting radially beyond said spindle for recurrent engagement by successive striker rolls; the striker means of each hammer block means being progressively offset circumferentially of the spindle from the axially outer end of the hammer block means to the axially inner end thereof; whereby each striker means is progressively engaged by each striker roll so that force is progressively applied longitudinally of each die block means.

3. In a swaging machine, a rotary spindle having an axially elongated diametrically extending slot therein; a series of die blocks movably mounted in longitudinally aligned juxtaposed relation in the slot; an annular series of integral striker rolls embracing said spindle, each striker roll extending parallel to the spindle axis and

axially beyond each end of the slot; and a series of hammer blocks movably mounted in longitudinally aligned juxtaposed relation in the slot outwardly of the die blocks and each engaged with a different die block; each hammer block having a striker element projecting beyond its outer end for recurrent engagement by successive striker rolls; successive striker elements being progressively offset circumferentially of the spindle in the same direction from one end of the series of hammer blocks to the other end thereof; whereby the striker elements are successively engaged by each striker roll so that force is successively applied to each die block longitudinally of said series of die blocks.

4. In a swaging machine, a rotary spindle having an axially elongated diametrically extending slot therein; a series of die blocks movably mounted in longitudinally aligned juxtaposed relation in the slot; an annular series of integral striker rolls embracing said spindle, each striker roll extending parallel to the spindle axis and axially beyond each end of the slot; and a series of hammer blocks movably mounted in longitudinally aligned juxtaposed relation in the slot outwardly of the die blocks and each engaged with a different die block; each hammer block having a hammer roll rotatably mounted therein and projecting beyond its outer end for recurrent engagement by successive hammer rolls; successive hammer rolls being progressively offset circumferentially of the spindle in the same direction from one end of the series of hammer blocks to the other end thereof; whereby the hammer rolls are successively engaged by each striker roll so that force is successively applied to each die block longitudinally of said series of die blocks.

5. In a swaging machine, a rotary spindle having an axially elongated diametrically extending slot therein; a series of die blocks movably mounted in longitudinally aligned juxtaposed relation in the slot; an annular series of integral striker rolls embracing said spindle, each striker roll extending parallel to the spindle axis and axially beyond each end of the slot; and a series of hammer blocks movably mounted in longitudinally aligned juxtaposed relation in the slot outwardly of the die blocks and each engaged with a different die block; each hammer block having a striker element projecting beyond its outer end for recurrent engagement by successive striker rolls; successive striker elements being progressively offset circumferentially of the spindle in the same direction from one end of the series of hammer blocks to the other end thereof; whereby the striker elements are successively engaged by each striker roll so that force is successively applied to each die block longitudinally of said series of die blocks; the first and last striker elements of the series being disposed on opposite sides of and substantially equally distant from an axial plane through the series of die blocks and hammer blocks.

6. In a swaging machine, a rotary spindle having an axially elongated diametrically extending slot therein; a series of die blocks movably mounted in longitudinally aligned juxtaposed relation in the slot; an annular series of integral striker rolls embracing said spindle, each striker roll extending parallel to the spindle axis and axially beyond each end of the slot; and a series of hammer blocks movably mounted in longitudinally aligned juxtaposed relation in the slot outwardly of the die blocks and each engaged with a different die block; each hammer block hav-

ing a hammer roll rotatably mounted therein; successive hammer rolls being progressively offset circumferentially of the spindle in the same direction from one end of the series of hammer blocks to the other end thereof; whereby the hammer rolls are successively engaged by each stroker roll so that force is successively applied to each die block longitudinally of said series of die blocks; the first and last hammer rolls of the series being disposed on opposite sides of and substantially equally distant from an axial plane through the series of die blocks and hammer blocks.

7. In a swaging machine, a rotary spindle having an axially elongated diametrically extending slot therein; a series of die blocks movably mounted in longitudinally aligned juxtaposed relation in the slot; an annular series of integral striker rolls embracing said spindle, each striker roll extending parallel to the spindle axis and axially beyond each end of the slot; and a series of hammer blocks movably mounted in longitudinally aligned juxtaposed relation in the slot outwardly of the die blocks and each engaged with a different die block; each hammer block having a hammer roll rotatably mounted therein; successive hammer rolls being progressively offset circumferentially of the spindle in the same direction from one end of the series of hammer blocks to the other end thereof; whereby the hammer rolls are successively engaged by each striker roll so that force is successively applied to each die block longitudinally of said series of die blocks; the first and last hammer rolls of the series being disposed on opposite sides of and substantially equally distant from an axial plane through the series of die blocks and hammer blocks, the hammer roll axes being parallel to the striker roll axes.

8. In a swaging machine, a rotary spindle having an axially elongated diametrically extending slot therein; a pair of die blocks mounted in the slot on opposite sides of the spindle axis; an annular series of integral striker rolls embracing said spindle, each striker roll extending parallel to the spindle axis and axially beyond each end of the slot; and a pair of hammer blocks mounted in the slot outwardly of the die blocks and each engaged with a different die block; each hammer block having a striker element projecting beyond its outer end for recurrent engagement by successive striker rolls; and the striker element of each hammer block means extending diagonally thereacross at an angle to the axes of the striker rolls; whereby each striker element is progressively engaged by each striker roll so that force is progressively applied longitudinally of each die block.

9. In a swaging machine, a rotary spindle having an axially elongated diametrically extending slot therein; a pair of die blocks mounted in the slot on opposite sides of the spindle axis; an annular series of striker rolls embracing said spindle, each striker roll extending parallel to the spindle axis and axially beyond each end of the slot; the radially inner work engaging surfaces of the die blocks being longitudinally curved so that such surfaces may rock longitudinally on each other; and a pair of hammer

blocks mounted in the slot outwardly of the die blocks and each engaged with a different die block; each hammer block having a striker element projecting beyond its outer end for recurrent engagement by successive striker rolls; and the striker element of each hammer block means extending diagonally thereacross at an angle to the axes of the striker rolls; whereby each striker element is progressively engaged by each striker roll so that force is progressively applied longitudinally of each die block.

10. In a swaging machine, a rotary spindle having an axially elongated diametrically extending slot therein; a pair of die blocks mounted in the slot on opposite sides of the spindle axis; an annular series of striker rolls embracing said spindle, each striker roll extending parallel to the spindle axis and axially beyond each end of the slot; the radially inner work engaging surfaces of the die blocks being longitudinally curved about relatively large radii of curvature so that such surfaces may rock longitudinally on each other; and a pair of hammer blocks mounted in the slot outwardly of the die blocks and each engaged with a different die block; each hammer block having a striker element projecting beyond its outer end for recurrent engagement by successive striker rolls; and the striker element of each hammer block means extending diagonally thereacross at an angle to the axes of the striker rolls; whereby each striker element is progressively engaged by each striker roll so that force is progressively applied longitudinally of each die block.

11. In a swaging machine, a rotary spindle having an axially elongated diametrically extending slot therein; a pair of die blocks mounted in the slot on opposite sides of the spindle axis; an annular series of striker rolls embracing said spindle, each striker roll extending parallel to the spindle axis and axially beyond each end of the slot; the radially inner work engaging surfaces of the die blocks being longitudinally curved about relatively large radii of curvature so that such surfaces may rock longitudinally on each other; and a pair of hammer blocks mounted in the slot outwardly of the die blocks and each engaged with a different die block; each hammer block having a rib projecting beyond its outer end for recurrent engagement by successive striker rolls; and the rib on each hammer block means extending diagonally thereacross at an angle to the axes of the striker rolls; whereby each rib is progressively engaged by each striker roll so that force is progressively applied longitudinally of each die block.
